CLAIM

The ornamental design for a camera, as shown and described.

DESCRIPTION

FIG. 1 is a front top perspective view of a camera showing our new design;

FIG. 2 is a front bottom perspective view thereof;

FIG. 3 is a rear top perspective view thereof;

FIG. 4 is a top plan view thereof;

FIG. 5 is a bottom plan view thereof;

FIG. 6 is a right-side elevational view thereof;

FIG. 7 is a left-side elevational view thereof;

FIG. 8 is a rear elevational view thereof; and,

FIG. 9 is a front elevational view thereof.

The broken lines depict portions of the camera in which the design is embodied that form no part of the claimed design. The broken lines shown which are immediately adjacent to the shaded areas represent the bounds of the claimed design and form no part of the claimed design.

1 Claim, 9 Drawing Sheets
